UNITED STATES PATENT OFFICE.

ROBERT O. KING, OF BUFFALO, NEW YORK.

BUILDING.

1,076,290.

Specification of Letters Patent.

Patented Oct. 21, 1913.

Application filed March 18, 1910. Serial No. 550,159.

To all whom it may concern:

Be it known that I, ROBERT O. KING, a citizen of Canada, residing at Buffalo, in the county of Erie and State of New York, have 5 invented new and useful Improvements in Buildings, of which the following is a specification.

This invention relates to a building construction which is more particularly de- 10 signed for green houses.

The object of this invention is to improve the construction of the green house in various respects with a view of increasing the strength and durability of the same, to fa- 15 cilitate the manufacture and erection of the same, to provide improved means of carrying off the drip water, and to reduce the shadows within the building to a minimum.

In the accompanying drawings consisting 20 of 3 sheets; Figure 1 is a fragmentary vertical transverse section of a green house embodying my improvements. Fig. 2 is a fragmentary vertical longitudinal section in line 2—2, Fig. 1. Fig. 3 is a fragmentary 25 vertical section, on an enlarged scale, showing the one form of my improved means for connecting a side post, rafter, and eave and also the adjacent corner brace and part 30 of the rafter truss. Figs. 4 and 5 are fragmentary vertical sections in the correspondingly numbered lines in Fig. 3. Figs. 6 and 35 7 are fragmentary horizontal sections in lines 6—6 and 7—7, Fig. 3, respectively. Fig. 8 is a perspective view of the rafter, 40 eave and sidepost connection. Fig. 9 is a fragmentary vertical transverse section, on an enlarged scale, showing the means for connecting the upper ends of a pair of companion rafters with the ridge and support- 45 ing the upper ends of the truss rods. Fig. 10 is a horizontal section in line 10—10, Fig. 9. Fig. 11 is a fragmentary vertical cross section, on an enlarged scale, showing the means for supporting the gutter between 50 laterally extended roofs and the adjacent rafters, trusses and corner braces. Figs. 12 and 13 are fragmentary perspective views of parts of the fixture for connecting a side post, rafter and eave and supporting a gut- 55 ter. Fig. 14 is a cross section showing a modification of the means for adjustably connecting a rafter with its foot piece or base. Fig. 15 is a fragmentary vertical transverse section showing the application 60 of my improvements to a tubular eave. Fig. 16 is a fragmentary vertical section showing

the means for supporting a tubular eave between the side posts. Fig. 17 is a similar view showing my invention embodied in a wood eave.

Similar letters of reference indicate corresponding parts throughout the several views.

Referring to Figs. 1, 3 and 11, A represents one of a row of tubular side posts of 65 a green house the lower end of which is set in a concrete wall a, and B one of a row of tubular center posts arranged between the sections of the green house which is set at its lower end in a concrete foundation b. 70 Lengthwise between the two rows of posts is arranged an elevated ridge C which is preferably constructed of wood although not necessarily so. Extending transversely between the upper ends of the posts and the 75 ridge are a plurality of inclined tubular rafters D, D' which together with the posts and ridge constitute the main frame which supports the various parts of the side walls and roof of the building. By constructing 80 the rafters of tubes or pipes a support is provided for the roof which is very strong, light and inexpensive and a minimum ob- struction is presented to the entrance of light into the green house. The rafters are 85 preferably so arranged that a rafter on one side of the ridge is in line with a rafter on the other side of the ridge. The upper ends of each pair of rafters which are in line and on opposite sides of the ridge are con- 90 nected with each other and with the ridge pole by a coupling which is preferably con- structed as follows: E, E represent two tops or coupling sections, each of which com- 95 prises an upright bracket e secured at its upper end to the underside of the ridge by bolts e¹ or otherwise and provided at its lower end with a laterally projecting socket e² in which the upper end of one of the tubular rafters is secured. The brackets of both 100 rafter tops overlap each other transversely of the ridge and are secured to each other by means of a bolt e³ passing through the lower parts thereof, as shown in Fig. 9. The brackets of one rafter and ridge coupling 105 are connected with the brackets of the adjacent couplings of the same character by means of longitudinal truss rods e⁴ each of which engages with its central part against the lower end of a strut e⁵ depending from 110 the underside of the ridge while each of its ends passes through openings in a pair

of coöperating brackets *e* and is provided with a screw nut *e*⁶ engaging with the far bracket. Each pair of brackets *e* receives the opposing ends of two truss rods *e*⁴, said rods being arranged side by side and one having its nut *e*⁶ bearing against the outer side of one bracket and the other having its nut bearing against the outer side of the other bracket. The two sections of the rafter and ridge coupling are made right and left and can therefore be cast alike and secured reversely to each other, thereby reducing the cost of manufacture and facilitating erection of the green house. At its lower end each inner rafter *D*¹ is connected with the upper end of each inner post *B* by means of a head *F* having a socket *f* on its lower part which receives the upper end of the post *B*, perforated ears *f*¹ arranged on opposite sides of said head, a lower inner base or fitting composed of a socket *f*² which receives the lower end of the adjacent inner rafter and which is provided at its lower end with a perforated ear *f*³ which is pivotally connected by a horizontal bolt *f*⁴ with the perforated ear *f*¹ on the adjacent side of the head *F*, as shown in Figs. 1 and 11.

The lower end of each outer rafter *D* is connected with the upper end of a side post by means of a rafter base composed of a socket *G* which receives the lower end of a rafter and is provided with a perforated ear *g* at its lower end, a post top or cap having a socket *H* which receives the upper end of the side post and is provided with a perforated ear *h* at its upper end which engages with one side of the ear *g* and is pivotally secured thereto by a horizontal bolt *g*¹. The sockets *f* and *H* are preferably secured to the upper ends of their respective posts *D*¹, *D* by screw joints, as shown in Figs. 1, 3 and 11. The opposite ends of each rafter may also be secured by screw joints in the top and base fittings thereof, as shown in Figs. 1, 3, 9 and 11, so as to permit of screwing these rafters into the sockets of the rafter tops and bases as far as required for adapting the length of the rafter to the width of the roof. Instead of employing a screw joint between the rafter and its top and base, the socket of each of these fittings may be split, as shown at *I* in Fig. 14, and the rafter *D*² may be held frictionally in said socket by a clamping screw *i* connecting the parts of the socket *I* on opposite sides of its split and drawing the same against said rafter. By means of the pivotal connection between the lower ends of the rafters and the top or heads of the posts the same can be readily turned relatively to the posts to suit the position of the latter.

For the purpose of holding each post and rafter in position relatively to each other and producing a strong and rigid struc-

ture, means are provided for bracing these parts on the inner side of the corner between the same. This is preferably effected by upper and lower brackets *J*, *J*¹ secured respectively by clips *j*, *j*¹ to the rafter and post, upper and lower swivels *K*, *L* the upper one of which has a lower internally screw threaded socket *k* and an upper perforated ear *k*¹ which is pivoted by a horizontal bolt *k*² to the upper bracket *J* while the lower swivel *L* has an upper internally screw threaded socket *l* and a lower perforated ear *l*¹ which is pivotally connected with the lower bracket *J*¹ by a horizontal bolt *l*², and an inclined brace *J*² preferably consisting of a tube or pipe and provided at its upper and lower ends with external screw threads which work in the threaded sockets *k*, *l*. The threads at opposite ends of the brace *J*² are right and left and the threads of the sockets with which they coöperate trend in the corresponding direction. It is therefore possible by simply turning the brace in one direction or the other to accurately shift the rafter and post into proper angular position relatively to each other and after such adjustment these parts are reliably held in position.

The roof of the green house may be of any suitable construction but as shown in the drawings the same preferably comprises purlins *N* secured lengthwise to the upper side of the rafters, roof sash bars *n* secured transversely to the upper side of the purlins and glazed sashes *n*¹ arranged above the purlins and sash bars and extending transversely from the ridge to the side of the building.

When the green house comprises a plurality of sections, a gutter *o* is arranged lengthwise at the bottom of the valley between the companion sloping roof sections, so that the same discharge the water from the upper sides into said gutter. The latter is supported on the upper side of the heads *F* at the top of the inner posts *B*, as shown in Figs. 1 and 11. Below the gutter the heads of the posts *B* also carry a drip pan *o*¹ into which flows the water of condensation on the underside of the sashes of the adjacent roof sections.

Arranged lengthwise at the lower edge or eave of the outer roof section is an eave bar to which the lower ends of the roof sash bars are secured. Between the eave bar and the concrete lower part *a* of the side wall are arranged the side sashes *a*¹. This eave bar may be variously constructed, for instance, as shown in Figs. 1 and 3, the same may be constructed in the form of an angle iron having an upper flange *p* which is arranged in line with the plane of the adjacent roof section and a lower flange *p*¹ which depends from the inner edge of the upper flange. Lengthwise below the inner or

lower flange of the eave bar is arranged a drip pan or gutter g which catches the drippings from the underside of the outer roof section.

5 The eave bar and side drip pan are supported on the corners of the side posts and rafters by means of brackets R each of which is provided at its upper end with lugs r which are secured to the inner side of the 70 lower flange of the angle iron eave bar and with lugs r^1 which are secured to the lower end of the adjacent sash bar while its lower end is provided with a perforated ear r^2 which is preferably arranged between the 75 ear h of the adjacent side post top and the ear g of the adjacent rafter base, these several ears being pivotally connected by the bolt g^1 . The ear r^2 of the eave bracket and the ear g of the rafter brace are preferably 80 interlocked so as to compel the same to always turn together about the bolt g^1 as an axis and thus keep the seats or faces r^3 , r^4 of the bracket R with which the eave bar and adjacent sash bar engage in such position 85 relatively to the rafter that the plane of the upper eave bar flange and the rafters are always parallel with the rafter, thereby permitting of turning the rafter freely on the side post for adjusting the parts during 90 the erection of the building without requiring any attention to keep the bracket R in the proper position for holding the eave bar and sash bar. The preferred means for thus causing the rafter and eave bracket 95 to turn together are shown in Figs. 8, 12 and 13 of the drawings and consist of a coupling key or rib s arranged on one side of the ear of the eave bracket and engaging with a corresponding groove or recess s^1 in 100 the opposing side of the ear of the rafter base. The key s and groove s^1 are formed integrally on their respective parts by casting and prevent assembling these parts in any other position except the correct one 105 in which the eave bracket stands in the proper position relatively to the rafter.

Between the upper part of the eave bracket and its lower ear the same is provided with an opening t which extends in 110 a direction lengthwise of the eave bar and which is adapted to receive and support the eave drip pan or gutter g . Within the eave bracket the eave drip pan is provided with a drain opening g^1 in its bottom.

115 Below the drip pan g the ear of the eave bracket is provided with a drain passage Q which extends from the drain opening g^1 of the pan downwardly to a drain opening g^2 in the upper end of the socket H of the 120 adjacent side post top. Any water dripping from the underside of the outer roof section into the eave pan or gutter passes successively through the opening g^1 of this gutter or pan, the drain passage of the eave bracket, the drain opening g^2 of the 125

top and into the side post from which latter the water is carried into the ground or to a sewer provided for that purpose. The opening g^2 of the post top is of sufficient area to permit the water to discharge into the same 130 from the drain passage of the eave bracket in the different positions which the latter is likely to assume when erecting the building.

Instead of constructing the eave bar of angle iron the same may be constructed in the form of a tube or pipe p^2 and arranged inside of the corner between the roof and wall of the building, as shown in Figs. 15 and 16. In this case the drippings from the underside of the roof run down—the inner side of the wall and the eave bar is connected with the post and rafter by a bracket R^2 which is connected at its upper end with the adjacent roof sash bar p^3 and side wall sash bar p^4 . Between the posts of the building the tubular eave bar is secured to the roof sash bar and wall sash bar by means of a loop or strap p^5 , as shown in Fig. 16. The three-piece corner fixture for connecting the post, rafter and eave bar is also applicable to a structure in which the eave bar consists of a wooden bar p^6 , as shown in Fig. 17, the eave bracket R^2 in this case being of suitable construction to fit this kind of eave bar.

Various means may be employed for stiffening or strengthening the rafters depending on the span of the roof. The means for this purpose shown in the drawings comprise a truss for each rafter consisting of a strut u depending from the central part of each rafter, a coupling u^1 arranged at the lower end of each strut, a single truss rod v extending from the coupling u^1 to the top 106 of the rafter, a pair of truss rods v^1 , v^2 arranged on opposite sides of each corner brace and extending from the coupling u^1 to the base of the rafter, and a connection w extending from the truss coupling u^1 of one 110 rafter to the other.

My improvements in green house construction permit of making the parts in the shop at low cost, so that they can be easily and quickly assembled on the ground without the necessity of any fitting. Furthermore, the different fixtures are of such character that the owner can readily assemble the same with tubes or pipes furnished by himself as is frequently done by green house 115 owners who are usually equipped with pipe and threading tools, thereby enabling a superior green house to be erected at comparatively low cost.

I claim as my invention:

1. A building having a ridge, rafters arranged on opposite sides of the ridge, and a coupling having two sections which are capable of vertical rotary adjustment relatively to one another, and each of which has 120 125 130

- an upwardly projecting part connected with the ridge and a laterally projecting part connected with one of the rafters.
2. A building having a ridge, rafters arranged on opposite sides of the ridge and a coupling connecting said rafters with each other and with the ridge comprising two sections each having an upright bracket secured at its upper end to said ridge and a socket projecting laterally from the lower end of the bracket and receiving the upper end of one of the rafters, said brackets overlapping each other transversely of the ridge, and a bolt connecting said brackets.
3. A building having a ridge, rafters arranged on opposite sides of the ridge and a coupling connecting said rafters with each other and with the ridge comprising two sections each having an upright bracket secured at its upper end to said ridge and a socket projecting laterally from the lower end of the bracket and receiving the upper end of one of the rafters, said brackets overlapping each other transversely of the ridge, and truss rods passing through said brackets,—one having a screw nut bearing against the outer side of one bracket and the other having a screw nut bearing against the outer side of the other bracket.
4. A building having a post, a rafter, an eave bar, a fitting comprising three sections which are connected with each other and which are also connected respectively with the eave bar, post and rafter, and an adjustable brace connecting the rafter and post.
5. A building having a post, a rafter, an eave bar, and a fitting comprising three sections which are connected with each other and which are also connected respectively with the post, rafter and eave bar.
6. A building having a post, a rafter, an eave bar, and means for pivotally connecting the post, rafter and eave bar comprising a top secured to the post and having an ear, a base secured to the rafter and having an ear, a bracket secured to the eave bar and having an ear, and a horizontal bolt connecting the several ears.
7. A building having a post, a rafter, an eave bar, a base secured to the rafter, a bracket fixedly connected with said base and with said eave bar, and a top secured to the post and pivotally connected with said bracket and base.
8. A building having a post, a rafter, an eave bar, and means for pivotally connecting the post, rafter and eave bar comprising a top secured to the post and having an ear, a base secured to the rafter and having an ear, a bracket secured to the eave bar and having an ear, a horizontal bolt connecting the several ears, and means for interlocking said bracket and rafter base.
9. A building having a post, a rafter, an eave bar, and means for pivotally connecting the post, rafter and eave bar comprising a top secured to the post and having an ear, a base secured to the rafter and having an ear, a bracket secured to the eave bar and having an ear, a horizontal bolt connecting the several ears, and means for interlocking said bracket and rafter base consisting of a key arranged on the ear of the eave bracket and engaging with a groove or recess in rear of the rafter base.
10. A building comprising a tubular post, a rafter connected with the post, an eave bar, a gutter arranged on the inner side of the building, and a bracket which supports said gutter and eave bar and which is provided with a drain passage leading from the gutter to the post.
11. A building comprising a tubular post, a top for said post consisting of a socket which receives the upper end of the post and is provided with a drain opening leading to the interior of the post and an ear projecting upwardly from the socket, a rafter, a base for said rafter consisting of a socket which receives said rafter and provided with an ear, an eave bar, a gutter having a drain opening, a bracket supporting said eave bar and gutter and having an ear and a drain passage leading from said gutter drain opening to the drain opening of the post top, and a coupling bolt connecting the ears of the post top, rafter base and bracket.

Witness my hand this 15th day of March, 1910.
